US0D1071132S

(12) **United States Design Patent** (10) **Patent No.:** **US D1,071,132 S**
(45) **Date of Patent:** **** Apr. 15, 2025**

(54) **EXTRACTOR HOOD**

(71) Applicant: **LG ELECTRONICS INC.**, Seoul (KR)

(72) Inventors: **Jisoo Lim**, Seoul (KR); **Miyoung Kim**, Seoul (KR); **Wonjun Lee**, Seoul (KR)

(73) Assignee: **LG ELECTRONICS INC.**, Seoul (KR)

(**) Term: **15 Years**

(21) Appl. No.: **35/520,973**

(22) Filed: **May 23, 2023**

(80) **Hague Agreement Data**

Int. Filing Date: **May 23, 2023**

Int. Reg. No.: **DM/229674**

Int. Reg. Date: **May 23, 2023**

Int. Reg. Pub. Date: **May 24, 2024**

(30) **Foreign Application Priority Data**

Dec. 21, 2022 (KR) 30-2022-0053921

(51) **LOC (15) Cl.** **23-04**

(52) **U.S. Cl.**

USPC **D23/372**

(58) **Field of Classification Search**

USPC D23/370, 372, 411

CPC F24C 15/20

(57) **CLAIM**

The ornamental design for an extractor hood as shown and described.

DESCRIPTION

1. Extractor hood
- 1.1 : Perspective
- 1.2 : Front
- 1.3 : Back
- 1.4 : Left
- 1.5 : Top
- 1.6 : Bottom
- 1.7 : Enlarged
- 1.8 : Perspective
- 1.9 : Perspective
- 1.10 : Perspective

The omitted right view is a mirror image of the left view; reproduction 1.7 is an enlarged view of the portion in reproduction 1.1; reproduction 1.8 shows a state in use of the claimed design; reproduction 1.9 shows a state of the filter being drawn out; reproduction 1.10 shows the claimed design in a closed state; the broken lines shown in the reproductions 1.1 to 1.7 depict portions of the extractor hood and form no part of the claimed design; all other broken lines shown in reproductions 1.8 to 1.10 illustrate environmental structure and form no part thereof; the dot-dot-dash lines illustrate the boundary and form no part thereof.

1 Claim, 10 Drawing Sheets
